UNITED STATES PATENT OFFICE.

FRANCIS M. SIMONDS, OF NEW YORK, N. Y.

FURNACE FOR TREATING ORES.

Application filed October 26, 1926. Serial No. 144,335.

In my pending application for United States patent, Serial Number 135,440, filed September 14th, 1926, I have described and claimed a novel form of furnace for the treatment of ore wherein a perforated hearth is in combination with means for supplying heated gases under pressure in such a manner that they pass upward through the hearth and act upon the comminuted ore 5 mass on the hearth to cause it to travel continuously through the apparatus and along the hearth. The process and apparatus forming the broad subject matter of the invention whereby this is accomplished are described and claimed in said earlier patent application.

The present invention relates to an improved form of hearth for use in furnaces analogous to that set forth in my said earlier application.

Broadly stated, the hearth forming the subject matter of the present invention differs from that described in my former application in that, instead of delivering the gases under pressure to move the ore upward through that portion of the hearth that actually supports the ore, I form my hearth in successive sections each comprising a supporting portion and a more or less upright perforate confining wall. Each supporting 20 portion of the successive hearth sections extends from the bottom of one perforate confining wall to the top of the next; so that, as the body of ore advances it falls from one wedge-shaped space to another. This promotes adequate agitation and insures subjecting every particle of comminuted material to the action of the hot gases.

As described in my aforesaid earlier application, I prefer to construct a long and relatively narrow hearth along which the comminuted ore is caused to travel, and under it to provide a series of wedge-shaped chambers, widening upward, into which the gases are forced and through which they find their way to the under side of the hearth. If desired, all or part of the combination whereby the gases are heated may take place in these chambers.

In the accompanying drawing I have shown in longitudinal section the preferred structure of my improved hearth, in connection with a single gas supply chamber. It will be understood that this principle of construction is repeated as often as necessary to obtain the total length of furnace desired in any instance.

In the accompanying drawing the opposite successive refractory confining walls of one of the preliminary gas-receiving chambers are shown at 10 and 11 respectively; it 60 being understood that the wall 10 is nearer the point where the ore mass is fed upon the hearth than the wall 11. In other words, the comminuted ore is supposed to move from right to left in the figure of drawing. 65

In the particular device illustrated there are four hearth sections in a single span from the wall 10 to the wall 11, each affording a wedge shaped pocket for the comminuted ore indicated at 12. Of course, any convenient 70 number of such sections might be used in each span without departing from my invention.

In the form shown, each section or pocket is formed by a more or less upright limiting 75 wall 13, provided with perforations 14, and an imperforate floor 15 which slopes gently upward from the bottom of its own perforated wall to the top of the next.

The steepness of the angle formed by each 80 floor section 15 with the horizontal may be indefinitely varied, as may the proportions of all the parts shown. In the specific device shown, the hearth as a whole conforms generally to the horizontal, but this is not 85 essential.

As indicated by the arrows in the drawing, gases under pressure, either preheated or allowed to burn within the spaces between the walls 10 and 11, are forced through the 90 perforations 14 in the walls 13, and, while acting chemically to roast or smelt the ore 12, they act to blow it forward and along the hearth. Thus crude ore may be fed in at one end and be continuously treated as it passes 95 along the step-shaped hearth, until discharged at the opposite end fully treated. As clearly set forth in my aforesaid earlier application, gases of different natures as to temperature, pressure, chemical constitution 100 or otherwise may be supplied at different successive parts of the hearth. This will, of course, depend upon what treatment it is found best to apply to the particular ore in hand. 105

At 16 is shown an asbestos filtering layer just above the ore, dividing it from the passage 17, under the refractory roof 18, through which passage the gases are drawn off, after acting on the ore, as described in my earlier 110 application. These elements form no part of the present invention.

What I claim is—

1. A furnace having a hearth formed in sections each of which comprises a floor and a perforate confining wall at one end thereof forming an angle with said floor.
2. A furnace as in claim 1 wherein successive gas supply chambers are provided under the hearth adapted to supply gas under pressure to the perforations in the confining walls.
3. A furnace as in claim 1 wherein the floor of each section extends from the bottom of one confining wall to the top of the next.

4. A furnace as in claim 1 wherein each floor section slopes upward from the bottom of the corresponding confining wall. 15

5. A furnace having a hearth composed of a series of pockets and means for admitting gas under pressure to the end of each pocket, whereby movement of ore along the hearth may be promoted. 20

In testimony whereof I have hereto affixed my signature on this 18th day of September, 1926.

FRANCIS M. SIMONDS.
